[57] **CLAIM**

The ornamental design for a protective shoe cover, substantially shown and described.

DESCRIPTION

FIG. 1 is a right-rear perspective view of a protective shoe cover showing my new design, the broken line showing being environmental only and forming no part of the claimed design;

FIG. 2 is a top plan view thereof;

FIG. 3 is a front elevational view thereof;

FIG. 4 is a left side elevational view thereof;

FIG. 5 is a rear elevational view thereof;

FIG. 6 is a bottom plan view thereof.

FIG. 1

FIG. 2

FIG. 3

FIG. 4

FIG. 5

FIG. 6
